ELECTRIC DISCHARGE DEVICE

Percy L. Spencer, West Newton, Mass., assignor
to Raytheon Manufacturing Company, Newton,
Mass., a corporation of Delaware

Application January 19, 1944, Serial No. 519,077

4 Claims. (Cl. 250—27.5)

1

This invention relates to a magnetron oscillator which is adapted to generate oscillations of hyper frequency and having wave lengths of the order of a few centimeters or less. Heretofore such oscillators have required a relatively complex anode configuration which was difficult to construct accurately and which tended to produce spurious oscillations, thus decreasing the efficiency of the oscillator.

An object of this invention is to devise a magnetron having an anode of simple construction wherein the frequency of oscillation is fixed by a simple and easily constructed configuration.

Another object is to provide a magnetron of the above type in which the oscillations are produced around a simple resonant slot in the wall of the anode.

A further object is to devise a simple coupling arrangement between a magnetron of the above type and a suitable wave transmission system, such as a wave guide.

The foregoing and other objects of this invention will be best understood from the following description of exemplifications thereof, reference being had to the accompanying drawings wherein:

Fig. 1 is a cross-section of a tube embodying the invention, said tube having a single oscillating slot and being associated with a hollow wave guide;

Fig. 2 is a cross-section taken along line 2—2 of Fig. 1;

Fig. 3 is a diagrammatic perspective view broken away to show an alternative mode of coupling the tube of Fig. 1 to a wave guide;

Fig. 4 is a cross-section of another embodiment of the invention wherein a plurality of oscillating slots are utilized;

Fig. 5 is a cross-section taken along 5—5 of Fig. 4; and

Fig. 6 is a fragmentary section similar to Fig. 4 showing an alternative mode of coupling to a wave guide.

The magnetron illustrated in Figs. 1 and 2 comprises a cylindrical anode 1 of suitable conducting material, such as copper, and a centrally located filamentary cathode 2 of the thermionic type. The anode and cathode are contained within a highly evacuated glass envelope 3 containing a reentrant stem 4. The anode 1 is supported by a conducting standard 5 sealed in the stem 4 and provided with a lead-in conductor 6 which is sealed through said stem and provides an external electrical connection for the anode. The cathode 2 is supported by a pair of con-

2

ducting standards 7, likewise sealed in the stem 4 and each provided with a lead-in conductor 8 sealed through said stem in order to provide external electrical connections to the cathode.

5 The cathode 2 may be provided with heating current through leads 8 so as to raise it to a temperature of thermionic emission. Light metal shields 9 may be provided at opposite ends of the electrode structure so as to prevent electrons from being projected through the ends of the anode 1 toward the glass walls of the envelope 3. These shields may be conveniently supported from the cathode standards 7. Magnet poles 10 and 11 are provided in order to create a magnetic field extending axially along the anode cylinder 1 and substantially parallel with the filamentary cathode 2. The anode 1 is provided with an elongated slot 12 cut through the wall of said anode in a direction substantially parallel with the axis of the anode cylinder. The slot 12 is narrow as compared with its length. Also its length is selected so as to be substantially one-half the wave length of the oscillations which the magnetron is adapted to generate.

10 When in the arrangement as described above the cathode is heated to temperature of thermionic emission, a suitable voltage is impressed between the cathode and the anode, and the magnetic field is of the proper value, oscillations 15 will be generated in the anode cylinder 1 around the slot 12. These oscillations will have a wave length which is substantially twice the length of the slot 12.

I believe that the operation of the device is 20 substantially as follows. The magnetic field set up about the cathode 2 causes the electrons, which are emitted from said cathode and accelerated by the anode voltage, to travel in orbital paths around the cathode 2. Thus in the vicinity

25 of the slot 12 electrons tend to travel past said slot in a direction normal to its length and induce varying electric charges on opposite sides of said slot. This tends to set up oscillations around the slot at a frequency at which the slot is resonant. The voltages set up across the slot react on the electrons passing the slot and tend to bunch these electrons in such a way that pulses of electrons periodically pass the slot with such periodicity and phase as to reinforce the above- 30 mentioned oscillations. As a result strong oscillations are generated which tend to radiate hyper frequency energy from the vicinity of said slot.

The energy radiated from the slot 12 may be 35 guided in a desired manner by inserting that por-

tion of the anode containing said slot into a wave guide 13. For example, the wave guide 13 may be provided with an opening 14 in one side thereof, and the upper end of the envelope 3 may be inserted through said opening 14 so that the slot 12 lies transverse to the wave guide 13. Under these conditions I believe that the energy coming from the slot 12 tends to excite the wave guide 13 in a so-called transverse magnetic mode in which the magnetic vectors are transverse to the wave guide and the electric vectors within the wave guide are substantially parallel to the direction in which energy is propagated through the wave guide. The wave guide 13 is designed to have proper dimensions for propagating the oscillations generated by the magnetron and is closed at one end by a conducting surface 15 spaced the proper distance from the slot 12 all in accordance with well known wave guide principles. Under these conditions the energy generated by the magnetron will be propagated through the wave guide 13 in the direction of the arrow P as shown in Fig. 2.

Instead of coupling the magnetron to a wave guide as described above, various other coupling arrangements may be devised. For example, as shown in Fig. 3, the magnetron may be inserted into one end of a rectangular wave guide 13 with the axis of the anode cylinder 18 substantially parallel with the long dimension of the cross-section of said wave guide. Likewise the slot 12 will be parallel to said long dimension. Under these conditions energy radiated from the slot 12 will be propagated along the wave guide 13. I believe that in this case the energy is propagated in a so-called transverse electric mode in which the electric vectors extend across the narrow dimension of the rectangular wave guide 13 and the magnetic vectors extend substantially parallel to the direction of propagation of the energy through the wave guide.

In most instances it may be desired to utilize a plurality of oscillating slots instead of a single slot, as shown in Figs. 1-3. Such a plural slot arrangement may take the form as shown in Figs. 4 and 5. This embodiment comprises a hollow cathode sleeve 16 within which is contained a heater filament 17. Surrounding the cathode 16 is an anode cylinder 18 formed of suitably conducting material, such as copper. The anode cylinder is provided with a plurality of slots 19, each similar to the slot 12, as described in connection with Figs. 1 and 2. As indicated, each of the slots 19 should have a length substantially equal to one-half of the wave length of the oscillations to be generated. When a magnetic field is set up parallel to the axis of the cathode 16 as will be described below, oscillations are generated about each of the slots 19. In order to feed these oscillations into a common output, a common wave guide is coupled to all of said slots 19. This wave guide consists of a hollow annular ring 20 open along its inner edge. The ring 20 likewise is made of a suitably conducting material, such as copper, and conveniently may be made in two halves which are soldered together so as to form an hermetic joint between said halves. The transverse cross-section of the ring 20 is preferably rectangular so as to cause said hollow ring to function as a rectangular hollow wave guide. The anode cylinder 18 is secured in the inner open side of the ring 20 in such a manner as to be in good electrical contact with said ring.

In order to produce the desired magnetic field, a pair of pole pieces 21 and 22 are hermetically

sealed in the lower and upper faces, respectively, of the ring 20. The pole pieces 21 and 22 are formed of some suitable magnetic material, such as steel. By sealing said pole pieces to the ring 20, as indicated above, an hermetically tight envelope is completed which may be highly evacuated and in which suitable electronic discharges may occur. Poles 23 and 24, of a suitably energized electromagnet or of a permanent magnet, are placed in contact with the pole pieces 21 and 22, respectively.

The cathode cylinder 16 comprises a tubular conducting sleeve coated with the usual electron emitting oxides. One end of the heater 17 within said sleeve is electrically connected to the top closed end thereof. The sleeve 16 is formed with a lower reduced tubular end 25 which passes through an opening 26 formed in the pole piece 21. The lower end of the reduced tubular section 25 fits into a recess in the upper end of a conducting rod 27 provided with a bore 28 through which an insulated wire 29 connected to the lower end of the heater 17 passes. The lower end of said insulated wire 29 passes out through a glass seal 30 carried from the lower end of the rod 27 by an intermediate sealing sleeve 31. Surrounding the rod 27 is a tubular metal shell 32, the upper end of which is inserted into an enlarged end of the openings 26 of the pole piece 21 and hermetically joined therewith as by brazing. To the lower end of the shell 32 is sealed a glass tube 33, the lower end of which is in turn sealed to a metal sealing cup hermetically fastened to the exterior of the rod 27. The conductor 29 serves as an external electrical connection to the heater 17, while the cup 34 serves as an external electrical connection to the cathode sleeve as well as to the upper end of said heater. Suitable electrical connection can be made to the anode cylinder 18 at any point on the ring 20 or at any of the conducting elements connected thereto.

In order to lead the energy from the wave guide 20 to a suitable utilization device, a coupling loop 35 is interposed in the space within said wave guide with the axis of said loop intercepted by the magnetic field within said wave guide. One end of the coupling loop 35 is electrically connected to the inner end of a pipe 36 hermetically sealed through a wall of the ring 20. The outer end of said coupling loop 35 is connected to a conductor 37 which passes through said pipe 36 and extends through a glass seal 38 carried at the outer end of said pipe 36.

When the device as described above is in operation, the oscillation energy generated around each slot 19 is fed into the wave guide 20 wherein it is propagated to the coupling loop 35 and conducted from the structure by the concentric line arrangement associated with said coupling loop. In order for the operation to proceed with maximum efficiency, it is desirable that the slots 19 be spaced from each other around the anode cylinder 18 by a distance substantially equal to one-half of the wave length of the oscillations within the wave guide 20. I believe that under the above conditions the slots 19 excite the wave guide 20 in a transverse magnetic mode whereby the oscillatory energy is effectively and efficiently transferred to the coupling loop 35 and led out of the device.

Other means of coupling the oscillatory energy within the wave guide 20 to an external wave guide may be utilized. For example, as shown in Fig. 6, a hollow wave guide 39 may be connected to the

exterior of the ring 20 and coupled to the interior of said ring by a coupling iris opening 40. It is to be understood that the wave guide 39 is hermetically sealed off at its outer end in a suitable manner, such as shown for example in the co-pending application of William C. Brown, Serial No. 506,608, filed October 16, 1943.

I have found that devices constructed in accordance with the foregoing principles can be made accurately with a minimum of difficulty. Further, such devices tend to oscillate at the desired output frequency and are remarkably free from tendencies to generate spurious oscillations which might tend to decrease the efficiency thereof.

Of course it is to be understood that this invention is not limited to the particular details as described above as many equivalents will suggest themselves to those skilled in the art.

What is claimed is:

1. A magnetron comprising: a cathode; an anode surrounding said cathode; and means adjacent said cathode and said anode for establishing a magnetic field in a direction transverse to the path therebetween; said anode having a plurality of perimetrical closed slots formed therein and spaced from each other around said anode by a distance substantially equal to the length of a half-wave at the frequency desired of the output of said magnetron; each of said slots being of a length substantially equal to a half-wave length in a direction parallel to that of said magnetic field.

2. A magnetron comprising: a cathode; an anode surrounding said cathode; and means adjacent said cathode and said anode for establishing a magnetic field in a direction transverse to the path therebetween; said anode including a toroidal cavity resonator, the inner wall of which is provided with a plurality of perimetrical closed slots spaced from each other around said wall by a distance substantially equal to the length of a half-wave at the frequency desired of the output of said magnetron; each of said slots being of a length substantially equal to a half-wave length in a direction parallel to that of said magnetic field.

3. A magnetron comprising: a cathode; an open-ended anode surrounding said cathode; and a pair of pole pieces sealed, respectively, to the

5 open ends of said anode for establishing a magnetic field in a direction transverse to the path between said cathode and said anode; said anode having a plurality of perimetrical closed slots formed therein and spaced from each other around said anode by a distance substantially equal to the length of a half-wave at the frequency desired of the output of said magnetron; each of said slots being of a length substantially equal to a half-wave length in a direction parallel to that of said magnetic field.

10 4. A magnetron comprising: a cathode; an open-ended anode surrounding said cathode; and a pair of pole pieces sealed, respectively, to the open ends of said anode for establishing a magnetic field in a direction transverse to the path between said cathode and said anode; said anode including a toroidal cavity resonator the inner wall of which is provided with a plurality of perimetrical closed slots spaced from each other around said wall by a distance substantially equal to the length of a half-wave at the frequency desired of the output of said magnetron; each of said slots being of a length substantially equal to a half-wave length in a direction parallel to that of said magnetic field.
